(57) CLAIM

The ornamental design for multiple facet gemstone, as shown and described.

DESCRIPTION

The patent or application file contains at least one drawing executed in color. Copies of this patent or patent application publication with color drawing(s) will be provided by the Office upon request and payment of the necessary fee. FIG. 1 is a side and top perspective view of a multiple facet gemstone showing my new design;

FIG. 2 is a top view thereof;

FIG. 3 is a bottom view thereof;

FIG. 4 is a side view thereof, the opposite side view being identical thereto; and,

FIG. 5 is a front view thereof, the rear view being identical thereto.
